UNITED STATES PATENT OFFICE.

RUSSELL H. BREMER, OF NEW YORK, N. Y., ASSIGNOR OF ONE-THIRD TO NICHOLAS DACUNTO AND ONE-THIRD TO ISADOR ERENBURG, BOTH OF NEW YORK, N. Y.

BOX-FORMING APPARATUS.

1,355,031.

Specification of Letters Patent.

Patented Oct. 5, 1920.

Application filed September 5, 1919. Serial No. 321,742.

To all whom it may concern:

Be it known that I, RUSSELL H. BREMER, a citizen of the United States, residing at New York, in the county of New York and State of New York, have invented new and useful Improvements in Box-Forming Apparatus, of which the following is a specification.

This invention comprehends the provision of a box forming apparatus, by means of which a box may be readily and easily formed from two separate strips of paper, cardboard or other suitable material.

The apparatus embodies among other features a male anvil member upon which the strips of material from which the box is formed are arranged, and a coöperating female member which bends against the anvil in the formation of the box.

20 The invention also contemplates an improved method of forming a box from separable strips of material, the finished article being reinforced about the open end thereof by means of wire or other suitable relatively stiff elements.

The nature and advantages of the invention will be better understood from the following detail description taken in connection with the accompanying drawing, the invention residing in the construction, combination and arrangement of parts as claimed.

30 In the drawing forming part of this specification, like numerals of reference indicate similar parts in the several views and where-

35 Figure 1 is a perspective view of the apparatus showing the initial arrangement of the strips from which the box is formed, and the normal position of the coöperating members of the form.

40 Fig. 2 is a vertical sectional view through the male anvil member of the form showing the strips bent against the sides and subsequently bent upwardly constituting the second step of the operation.

Fig. 3 is a view similar to Fig. 2 illustrating the third step of the operation.

45 Fig. 4 is a fragmentary detail view showing the upper edge of the box when completed.

The apparatus forming the subject matter of this invention, comprises a male anvil member indicated at 10, and a coöperating female member indicated at 11. In this 55 specific embodiment of the invention, a male

anvil member is mounted upon the base 12 and held stationary while the female member which receives the upper portion of the male member is movable toward and away from the latter. The male anvil member is 60 of substantially rectangular formation, the sides however converging from an appropriate point in the height of the member toward the top 13 thereof. Each side of the male anvil member is provided with a horizontally disposed elongated slot 14 for a purpose to be hereinafter described. It will be noted however, that the converging portion of each side merges into the straight portion thereof at a point approximately 65 in a plane with the transverse center of the slot 14 as clearly shown in Figs. 2 and 3. The female member 11 is supported immediately above the male anvil member by means of a yoke 15 terminally secured to the base 70 12 and straddling the anvil member 10. A tubular member 16 depends from the center of the yoke 15, for the reception of a rod 17 rising from the top of the female member, the rod passing through the yoke 15 and 75 provided with a knob 18. A spring 19 encircles the tubular member 16 and has one end secured to the top of the female member 11 and its opposite end secured to the yoke 15. The spring is tensioned to normally hold the female member 11 spaced 80 above the anvil member 10 an appreciable distance.

The apparatus described may be used in connection with the improved method of 85 forming a box from separate strips of paper or other suitable material indicated at 20. In practice, the strips 20 are arranged in crossed relation as shown in Fig. 1 and may be secured together in this manner by suitable paper fasteners or the strips may be 90 arranged in this manner to rest upon the top of the anvil 10 without being secured as shown in Fig. 1. Subsequent to the positioning of the strips 20 in this manner, the 95 female member is forcibly driven down upon the converging portion of the anvil member 10, by impact against the knob 18, it being understood that the female member 11 is of similar configuration as the upper 100 portion of the anvil member which it receives. Consequently, the projected extremities of the strips 20 are bent against the converging portions or sides of the male 105 anvil member 10. With the parts in this 110

position a single length of relatively stiff material, such as wire or the like is wrapped about the downturned portion of the strips 20 and the male anvil member 10 at a point 5 where the converging sides merge into the straight portion as shown in Fig. 2. If desired, the wire indicated at 21 may be first given a shape to conform to the configuration of the anvil member, and then slipped 10 down over the anvil in the downturned portion of the strips 20. In either instance however, the reinforcing element 21 occupies the position illustrated in Fig. 2, and the ends of the strips 20 are then bent upwardly as shown at 22. Prior to the placing 15 of the reinforcing element about the downturned portions of the strips 20, the female member 11 may be allowed to return to its normal elevated position, or if desired it 20 may be constructed of such size as to be frictionally maintained associated with the male anvil member until the reinforcing member 21 has been placed in position illustrated in Fig. 2. If the female member 11 is used in this manner, it will serve to hold 25 the sides of the strips 20 taut against the adjacent sides of the anvil member 10 until the reinforcing element is wrapped or otherwise properly placed about the downturned portions of the strips. After the 30 extremities of the strips 20 have been turned up over the reinforcing element 21 as shown in Fig. 2, an additional reinforcing element similar to the element 21 but indicated at 35 23 is placed about the upturned extremities as illustrated in Fig. 3. It might here be stated, that one side of each strip 20 is coated with an adhesive substance 24, and when the terminals of the strips have been 40 bent upwardly in the manner disclosed in Figs. 2 and 3, the adhesive side 24 of each strip is outermost. The reinforcing element 23 effectively maintains the reinforcing element 21 confined between the folds of the 45 strips, and when the reinforcing element 23 has been arranged in the manner as shown in Fig. 3, the terminals of the strip are then 50 bent downwardly over the reinforcing element 23, through the slots 14 and adhesively secured to the inner side of each strip. This arrangement is shown at the right hand side of Fig. 3, wherein the finally secured terminal of one strip is indicated at 55 25. The slots 14 are of sufficient size to provide for the insertion of the fingers within the anvil member 10, and in order to secure the terminals 25 of each strip against one side thereof. Obviously, the crossed portions of the respective strips constitute the 60 bottom of the box, indicated at 26 while the bent portions constitute the sides of the box. When the box has been thus formed, it is removed from the anvil 10 and as 65 shown in Fig. 4 the upper edge of the box is effectively reinforced by the elements 21

and 23 which are embedded in the folds of the material from which the box is formed.

While it is believed that the nature and advantages of the invention will be readily apparent from the foregoing description, I 70 desire to have it understood that I do not limit myself in this connection and that such changes may be resorted to when desired as fall within the scope of what is claimed.

Having thus described my invention what I claim as new is:—

1. In a box forming apparatus, male and female members, means for normally holding said members separated, said male member having sides including straight portions and angularly disposed portions, one of said members being movable toward and away from the other, and said male member having an elongated slot at each side.

2. In a box forming apparatus, a male anvil, a female member, yieldable means supporting the female member above said anvil, said female member being movable toward and away from said anvil, and said anvil having an elongated slot in each side thereof.

3. The herein described method of forming a box, consisting of crossing two strips of material, and arranging said strips upon an anvil, then bending the projecting portions of said strips against the sides of the anvil, then surrounding said portions of the strip with a reinforcing element, and then bending the terminals of said strips 100 against the latter and about the said reinforcing elements.

4. The herein described method of forming a box, consisting of crossing two strips of material, and arranging said strips upon an anvil, then bending the projecting portions of said strips against the sides of the anvil, then arranging a reinforcing element about the bent portions of the strip, then bending the strips upwardly and around the 110 reinforcing element, then placing a second reinforcing element about the upturned portions of the strip, and then finally bending the upturned portions over the second mentioned reinforcing element and adhesively 115 securing the terminals against the inner sides of said strips.

5. In a box forming apparatus, a base, male and female members, one of said members reposing upon the base, a yoke fixed 120 on said base, the other of said members being suspended from said yoke and movable toward and away from the member reposing upon the base, and yieldable means interposed between said yoke and its associated 125 member for normally holding the said members separated.

In testimony whereof I affix my signature.

RUSSELL H. BREMER.
